UNITED STATES PATENT OFFICE

EDWARD CRAIG, OF ST. JOSEPH, MICHIGAN; THE COMMERCIAL NATIONAL BANK
EXECUTOR OF SAID EDWARD CRAIG, DECEASED

WIREBOUND-BOX-BLANK MACHINE

Application filed March 24, 1928. Serial No. 264,330.

This invention relates to wire bound box blank machines of the kind in which means are provided for automatically stapling wires to sheets and cleats to form foldable wire bound blanks which can be folded and reduced to box form and loaded or filled and then closed by twisting together the ends of the wires in the well known manner.

Generally stated, the object of the invention is to provide a novel and improved construction and arrangement whereby high speed production of the blank is made possible, with a consequent reduction in cost of production, without interfering with the proper placing of the staples on the blank, and without unduly complicating the construction and mode of operation of a machine of this kind.

It is also an object to obviate the necessity of using certain features heretofore considered necessary or desirable in machines of this kind.

To the foregoing and other useful ends the invention consists in matters hereinafter set forth and claimed and shown in the accompanying drawings in which—

Fig. 1 is an end elevation of a machine embodying the principles of the invention.

Fig. 2 is a side elevation of said machine, with certain portions thereof omitted for convenience of illustration.

Fig. 3 is a longitudinal vertical section on line 3—3 in Fig. 1.

Fig. 4 is a similar section on line 4—4 in Fig. 1.

Fig. 5 is a detail section on line 5—5 in Fig. 4.

Fig. 6 is an enlarged horizontal section on line 6—6 in Fig. 1.

Fig. 7 is a vertical longitudinal section on line 7—7 in Fig. 6.

Fig. 8 is a transverse detail section on line 8—8 in Fig. 6.

Fig. 9 is a similar section on line 9—9 in Fig. 6.

Fig. 10 is a similar section on line 10—10 in Fig. 6.

Fig. 11 is a perspective of one of the stapler controller blocks on one of the endless feed belts.

Fig. 12 is a similar view of a similar block.

Fig. 13 is a similar view of one of the cleat pushers employed on the feed belts or sprocket chains employed to feed the cleats and sheets under the staplers.

Fig. 14 is an enlarged vertical longitudinal section on line 14—14 in Fig. 1.

Fig. 15 is a vertical transverse section on line 15—15 in Fig. 14.

Fig. 16 is a detail sectional view, of a fragmentary character, illustrating certain parts of the machine.

Fig. 17 is a similar view.

Fig. 18 is an enlarged detail section on line 18—18 in Fig. 16.

Fig. 19 is a detail section on line 19—19 in Fig. 18.

Fig. 20 shows the rule or graduated stick that is used in resetting the blocks on the feed belts for blanks of different sizes.

Fig. 21 is a plan of one of the blanks made on said machine.

Fig. 22 is a side or edge view of said blank.

Fig. 23 is a diagrammatic view showing the set up of feed blocks for the blank shown in Figs. 21 and 22.

As thus illustrated, the invention comprises a main frame comprising sides 1 and a base 2 and a transverse top 3, all rigidly held together and still further strengthened by the transverse bar 4 as shown. The general type of machine to which the invention relates is that in which a transverse shaft 5 is mounted in bearings 6 on the main frame, at the discharge end of the machine. A similar shaft (not shown) is suitably supported at any desired distance from the main frame of the machine, at the extreme left in Fig. 3, and sprockets 7 are mounted on these shafts to support the endless feed belts 8 that feed the cleats and sheets in the horizontal feeding plane of the machine. There should be sufficient length for these belts to facilitate the work of the attendant or operative in placing the cleats and sheets in the machine, and to accommodate the longest size blanks to be made. The links of these belts should be readily removable and replaceable, in any well known manner, so that the length of the belts can be varied at will, the machine hav-

ing well known provisions (not shown) for moving the sprocket shaft at the receiving end of the machine toward or away from the similar shaft 5 at the other end. As shown more clearly in Fig. 6, the belts 8 are provided with cleat adjustable and removable pushers 9 for pushing the cleats along in the parallel cleat guides 10, and these pusher blocks having sheet spacers 11 for spacing the sheets apart, as shown in Figs. 21 and 22 of the drawings. The endless feed belts have their upper stretches supported in guides 12 suitably supported by the general frame work of the machine.

15 The means for operating the belts 8 include an overhead shaft 13 connected by a sprocket chain 14 with the sprocket wheel 15 mounted on the adjustable bearing 16 carried on the outer side of the lower portion of one of the 20 sides 1 of the main frame. This sprocket 15 has keyed thereon a removable pinion 17 which engages a gear 18 removably mounted on the fixed spindle bearing 19 on the side frame. This gear has a sprocket 20 connected by a sprocket chain 21 with the sprocket 22 on the shaft 5 previously mentioned. This sprocket 22 has holes 23 therein (say thirteen holes), and the disk 24 has twelve holes 25 therein. The disk 24 is keyed to the 30 shaft 5, and a removable pin 26 is provided for insertion in the holes 23 and 25 to key the sprocket 22 to the shaft 5 in adjusted or desired relation to the feed belts 8, so that these belts can be stepped forward or back slightly, in adjusting the relation between the 35 positions of the blanks and the stapling mechanism, with a view to properly placing or positioning the staples on the blanks. In other words, the relation between the shaft 13 and the feed belts 8 can be adjusted or varied by the adjustment of the pin 26 from one to another of the holes 23 and 25, and with the difference in number of these two sets of holes rather fine adjustment if needed can always 40 be obtained. A clutch pulley 27 is provided on the shaft 13, controlled by a hand lever 28 suitably connected thereto. When the operator or attendant closes the clutch, the feed belts 8 operate continuously at a speed 45 proper for the laying of the cleats and sheets thereon while the belts are moving continuously.

50 The stapling mechanism for forming staples from wire fed thereto, and for driving the staples into the sheets and cleats, to secure the binding wire thereto, comprises a swinging or oscillating frame composed of side members 29 connected together at their upper ends by a rod or bar 30 and at their lower ends by the transverse flat bar 31 above which the blanks travel with the feed belts 8 in the direction indicated by the arrow 32 in Fig. 3 of the drawings. This stapler frame is supported on the bosses 33 of the frame 55 sides 1, forming trunnion bearings for the

members 29, and the shaft 13 is supported in these bearings, whereby the stapler frame oscillates about an axis coincident with the axis of the shaft 13 from which the blank feeding belts are continuously driven. The members 29 are also connected together rigidly by the flat bar 34 upon which as many staplers 35 are mounted as there are binding wires to be secured to the sheets 36 and cleats 37 of the blank shown in Figs. 20 and 21 of the drawings. The pushers 9 engage the shoulders 38 of the tongue and groove cleats, and the outer staplers insert the staples 39 through the sheets and cleats, over the outer binding wires, while the middle staplers insert staples 40 over the middle wires and through the sheets. Thus the middle rows of staples 40 have to be clinched on the under side of the sheets, but the staples 39 do not pass entirely through the cleats, so that the supports 41 85 for the cleats are not clinch blocks, whereas the two supports 42 have clinch blocks 43 to clinch the staples 40, and it will be understood that the supports 41 and 42 are all adjustably mounted on the beam 31 of the swinging stapler frame. Cams 44 on the shaft 13 engage rollers 45 on the staplers 35 and thus actuate these staplers in unison to drive four (or any number) staples each time the rollers 45 are forced downward by their allotted 95 cams.

100 The individual staplers 35 may be of any suitable character, but are, for example, of the kind shown in Figs. 14 and 15 of the drawings. As thus shown, the stapler comprises an ordinary staple former 46 and a staple driver 47 slidable therein, together with the usual loop bar 48 over which the staple former bends the length of wire into staple form. As the details of this type of staple forming 105 and driving means are old and well understood, further description thereof will not be necessary. But it is important to point out, however, that these staplers are adjustably mounted by the plates 49 and bolts 50 on the bar 34 of the swinging stapler mechanism frame, and that the bearings 51 of the upper ends of the staplers are also adjustable laterally, as are the cams 44, on the shaft 13 to 110 change the width of the blanks, and for this purpose, it will be understood, the blank feeding means and guides and all other necessary parts are also laterally adjustable.

115 With the foregoing construction, it is obvious that the stapling mechanism is movable with the blanks, while the staples are being driven, as the feed of the blanks and blank materials is continuous. For this purpose the stapler frame is oscillated at the same speed as the feed of the blanks, by the link or links 52 which are actuated by the crank arm 53 on the rock shaft 54, which latter is rocked by its arm 55 which is connected by a rod 56 with the eccentric device 57 on the shaft 13, the parts and motions being in 120 125 130

such timed relation that the staplers move forward a distance with the blanks each time the staples are driven, and then move backward to the normal position where they will again move forward for the driving of the next set of staples, this being repeated for each successive set of staples. While the stapling mechanism swings or oscillates about the shaft 13, the latter does not support the weight thereof, as the trunnion bearings 32 support such weight.

Each stapler has a wire feeding device of any suitable character. For example, as shown in Fig. 14 of the drawings the wire 58 is fed between the rolls 59 and 60 which are preferably geared together and operated by the shaft 61 upon which the roll 59 of each feed device is adjustably mounted. Each device also comprises a bracket plate which is slidable laterally on the shaft 61 and on the rod 62, and an eccentric adjuster 63 is provided for the roll 60 of each feeding device. Wire feeding devices of this kind are common and well known. However, in this case the said wire feeding devices are carried by brackets 64 on the side members 29 of the swinging stapler frame. Also, the shaft 61 is rotated intermittently by a ratchet device comprising the ratchet wheel 65 on said shaft, and the ratchet dog 66 on the oscillating member 67 on said shaft. A rod 68 connects said member 67 to the eccentric 69 on the shaft 13, whereby the latter serves also to actuate all of the wire feeding devices.

It is desirable, of course, to automatically cut out the formation and driving of staples where they are not needed or desired, and for this purpose the said ratchet device has an oscillatory shield 70 which is connected by a rod 71 to the arm 72 pivoted on the main frame of the machine. A bell crank is pivoted at 73 on the frame and has its arm 74 connected by a link 75 with said arm 72, and has its other arm 76 connected by a rod 77 to one end of the lever 78 which is pivoted at 79 to operate in a horizontal plane. This lever 78 has its other end provided with a roller 80 for engaging the blocks 81, 82, and 83 on the feed belt 8, the blocks 81 being set in position to prevent the driving of staples between sections of the same blank, and the blocks 82 and 83 being set in position to prevent the driving of staples between blanks. In other words, the oscillation of the shield 70 by the said blocks, each time a block engages the roller 80, throws out the dog 66 and prevents the feeding of wire for staples, and hence no staples are driven. The said blocks 81, 82, and 83 are adjustable on the belt 8 for blanks of different sizes.

A transverse rock shaft 84 is mounted to rock in bearings 85 on the main frame, and is provided with wire cutters (as many as there are wires to be cut) each comprising a fixed ledger blade 86 and a pivoted shearing blade

87, the shearing blades being all connected together for operation in unison by the rod 88, which latter is connected by a spring 89 to the adjacent bearing 85, whereby the cutting devices are normally open to receive the wires. The shaft is rocked by a rod 90 extending loosely through the arm 91 on said shaft, and said rod is connected at its other end to the eccentric 57 previously mentioned. When the cutters are over the blank, the rod 90 reciprocates in the arm 91 without causing any action. The cutters are held normally in raised position by an arm 92 on the shaft 84, said arm being normally held down by engagement with the locking lever 93 which is pivoted at 94 in position to have its cam portion 95 engaged by the cam portion 96 of each block 83, whereby the cutters are automatically released and allowed to move downward of their accord whenever a gap between blanks passes underneath, so that the cutter blades move down upon the binding wire. The cutters are then actuated to cut the wires by an arm 97 which engages the end of the rod 88, and which is pivoted at 98 on the frame of the machine. The crank arm 99 of this arm 97 is connected by a rod 100 with the swinging frame member 29, whereby when the cutters are down the rod 88 is given a quick endwise movement by the arm 97 to cause the cutters to cut the wire between blanks. When the cutters are up, the arm 97 simply swings back and forth idly, and the rod 90 slides idly back and forth as stated. After the wires are cut the nut 101 on the rod 90 pulls the arm 91 backward, thus raising the cutters, and the spring controlled latch arm 93 then re-engages the arm 92 and again locks the cutters in raised position until the next gap between blanks arrives below, and the cutting operation is repeated.

The pivoted arms 102 have portions 103 for engaging the front ends of the cleats, and are provided with springs 104 to cause these portions to rub on the inner sides of the cleats. Thus the cleats if displaced forwardly apart from their pushers 9, will be forced back by the portions 103 into correct position, whereby there is automatic rectification of any misplacement or displacement of the cleats.

When the speed of the feed belts 8 is varied, to vary the spacing between the staples, it is desirable, of course, that the speed of movement of the swinging staplers be changed accordingly, so that the staplers and the feed belts and the work will move forward in unison while the staples are being inserted. This, it is found, is easily taken care of by the slack and lost motion in the feed belts and other parts, but means for positively changing the speed of motion of the swinging staplers can be provided, if desired, as shown in Figs. 3 and 17 of the drawings, in which the rod 56 is connected to a block 105 which is slidable on the arm 55, and which

may be adjusted back and forth on the arm by the screw 106 in a manner that will be readily understood. This, in effect, lengthens and shortens the arm 55, thus changing the throw or speed of travel of the swinging 5 staplers, and this adjusting device can be employed to regulate the throw or speed of travel of the staplers in accordance with the speed of travel of the feed belts. If the feed 10 belts are traveling relatively fast, in order to space the staples a greater distance apart, then the staplers will need to travel faster and a greater distance, and this can be provided for by the slack or lost motion in the 15 belts or other parts, as stated, or by the provision of the adjusting elements 105 and 106 as shown and described.

The spacing of the staples for blanks of 20 different sizes can be determined by any suitable or desired means. For example, Fig. 20 shows a stick or ruler graduated differently at different edges thereof, and a stick or ruler of this kind can be held up beside the feed chains to determine the adjustments 25 required for any particular spacing of the staples.

What I claim as my invention is:

1. In wire bound box blank machinery, in combination, instrumentalities for continuously feeding the blank materials, a transverse rotary shaft disposed above the feeding plane of said instrumentalities, swinging stapling mechanism the transverse axis of oscillation of which is also above said plane, actuating means including an oscillatory rock shaft deriving power through a reciprocating element from said rotary shaft to oscillate said mechanism about its said axis, whereby said mechanism moves a distance with the blank materials while inserting staples therein, cam means on said rotary shaft to actuate said mechanism, and driving means to controllably rotate said shaft.

2. A structure as specified in claim 1, said instrumentalities having an adjustable driving connection with said rotary shaft operative to cause continuous feeding of the blank materials at the same speed that said mechanism is oscillated by said shaft.

3. A structure as specified in claim 1, comprising rotary wire feeding devices on said mechanism, and operating elements including a cam device on said rotary shaft to operate said devices.

55. 4. A structure as specified in claim 1, comprising a wire cutter for severing the binding wire between blanks, and an operating connection between said cutter and the frame of said mechanism, whereby the oscillation 60 of said mechanism actuates the wire cutter.

5. A structure as specified in claim 1, said mechanism having a frame, and trunnion bearings to support said frame and whereby the axis of oscillation of said mechanism is 65 coincident with the axis of said rotary shaft,

70 preventing said shaft from sustaining the weight of said mechanism frame, said bearings also supporting said shaft.

6. A structure as specified in claim 1, said rock shaft having an actuating eccentric cam device therefor on said rotary shaft.

7. A structure as specified in claim 1, comprising adjusting means for setting said feeding instrumentalities either forward or backward in relation to said stapling mechanism.

8. A structure as specified in claim 1, comprising wire feeding devices for and mounted to swing with said mechanism, and means on said rotary shaft to actuate said devices.

9. A structure as specified in claim 1, comprising wire feeding devices for and mounted to swing with said mechanism, and means on said rotary shaft to actuate said devices, together with means automatically controlled by the feeding motion of said instrumentalities to govern said devices and prevent the feeding of wire where staples are not desired.

10. In wire bound box blank machinery, in combination, instrumentalities for continuously feeding the blank materials, a transverse rotary shaft disposed above the feeding plane of said instrumentalities, swinging stapling mechanism the transverse axis of oscillation of which is also above said plane, actuating means deriving power from said shaft to oscillate said mechanism about its said axis, whereby said mechanism moves a distance with the blank materials while inserting staples therein, cam means on said shaft to actuate said mechanism, driving means to controllably rotate said shaft, a wire cutter for severing the binding wire between blanks, and an operating connection between said cutter and the frame of said mechanism, whereby the oscillation of said mechanism actuates the wire cutter.

11. In wire bound box blank machinery, in combination, instrumentalities for continuously feeding the blank materials, a transverse rotary shaft disposed above the feeding plane of said instrumentalities, swinging stapling mechanism the transverse axis of oscillation of which is also above said plane, actuating means deriving power from said shaft to oscillate said mechanism about its said axis, whereby said mechanism moves a distance with the blank materials while inserting staples therein, cam means on said shaft to actuate said mechanism, and driving means to controllably rotate said shaft, said actuating means comprising a rock shaft and an actuating eccentric cam device therefor on said rotary shaft.

12. In wire bound box blank machinery, in combination, instrumentalities for continuously feeding the blank materials, a transverse rotary shaft disposed above the feeding plane of said instrumentalities, swinging sta-

pling mechanism the transverse axis of oscillation of which is also above said plane, actuating means deriving power from said shaft to oscillate said mechanism about its said axis, whereby said mechanism moves a distance with the blank materials while inserting staples therein, cam means on said shaft to actuate said mechanism, driving means to controllably rotate said shaft, and adjusting means for setting said feeding instrumentalities either forward or backward in relation to said stapling mechanism.

13. In wire bound box blank machinery, in combination, instrumentalities for continuously feeding the blank materials, a transverse rotary shaft disposed above the feeding plane of said instrumentalities, swinging stapling mechanism the transverse axis of oscillation of which is also above said plane, actuating means deriving power from said shaft to oscillate said mechanism about its said axis, whereby said mechanism moves a distance with the blank materials while inserting staples therein, cam means on said shaft to actuate said mechanism, driving means to controllably rotate said shaft, wire feeding devices for and mounted to swing with said mechanism, and means on said rotary shaft to actuate said devices.

14. In wire bound box blank machinery, in combination, instrumentalities for continuously feeding the blank materials, a transverse rotary shaft disposed above the feeding plane of said instrumentalities, swinging stapling mechanism the transverse axis of oscillation of which is also above said plane, actuating means deriving power from said shaft to oscillate said mechanism about its said axis, whereby said mechanism moves a distance with the blank materials while inserting staples therein, cam means on said shaft to actuate said mechanism, driving means to controllably rotate said shaft, wire feeding devices for and mounted to swing with said mechanism, means on said rotary shaft to actuate said devices, and means automatically controlled by the feeding motion of said instrumentalities to govern said devices and prevent the feeding of wire where staples are not desired.

50 Specification signed this 21st day of March,
1928.

EDWARD CRAIG.
